(57) **CLAIM**

The ornamental design for a sloped plate conditioner insert, as shown and described.

DESCRIPTION

FIG. 1, is an isometric view of my new sloped plate conditioner insert, showing the top;

FIG. 2, is a side elevational view of said insert thereof;

FIG. 3, is a top view of said case insert, shown at twice scale of FIG. 2, to illustrate the apertures in said top thereof; and, FIG. 4, is a bottom view of said insert, shown at twice scale of FIG. 2, to illustrate the apertures in said bottom thereof.
